UNITED STATES PATENT OFFICE.

ROBERT A. BLAKE, OF BROOKLYN, NEW YORK.

ELECTROMAGNET.

Application filed May 26, 1924. Serial No. 715,802.

This invention relates to electromagnets particularly adapted for imparting power to various mechanisms and the objects of the invention are to produce a device of this 5 character which is of simple and economical construction, durable in use, and effective in operation.

To this end, my invention consists in the novel construction, arrangement and combination of parts herein shown and described and more particularly pointed out in the 10 claim.

In the accompanying drawings, I have shown one construction by way of example, 15 in which my invention may be employed and which will be described, it being premised however that various changes may be made in the details of construction and arrangement by those skilled in the art without 20 departing from the spirit and scope of my invention as defined by the appended claim.

Referring to the drawings, Fig. 1 is a side elevation of the device; Fig. 2 is a transverse vertical cross section of the solenoid 25 showing plunger, rod and other parts; Fig. 3 is a transverse vertical section showing the end view of the solenoid with plunger and rod; Fig. 4 is a cross section through line 4—4 of Fig. 2; Fig. 5 is a cross section 30 through line 5—5 of Fig. 2.

To show how this electromagnet may be operated, I illustrate by advertizing to the construction which, as an example, I show in the drawings, wherein like numerals of 35 reference indicate like parts. Upon the main base 10 are holes as shown at 12 for intake and expulsion of air to assist in keeping the solenoid 17 and the plunger 13 cool. 18 is an iron shield partly surrounding magnetic wire coil 20 of solenoid 17 and is sometimes termed an iron clad and, in the illustrated example, constitutes a part of the magnetic circuit of the solenoid 17. 19 is a bobbin of brass or of indurated fiber or of 40 other non-magnetizable material on which wire coil 20 is wound. 13 is a hollow iron plunger independent of solenoid 17 and contains apertures or holes as shown at 14 and having bearings as shown at 15. At each 45 bearing end of plunger are holes or apertures as shown at 16 pierced through to allow air to enter and pass while plunger 13 is in motion. In other words, said bearings are air cooled. 21 is a guide rod upon which 50 the hollow plunger 13 is adapted to slide. 22 indicates structural rods of non-magnetizable material to which the cross bar 23 is attached in order to support the guide rod 21, a bearing 11 supporting the opposite end of rod 21; the structural rods 22 may be 55 fastened to the ironclad case by any approved method. 24 indicates two pitman bars attached to hollow plunger 13 and are provided with two spaced collars pivotally connected at 25 to one end of the walking beam 26; the latter swings on frame 27 and at that end which is opposite to 25 carries a link 28 connected to a holder rod 28' to carry the counterweights 29 movable on a guide rod 30'. A shock absorbing spring 30 on 60 guide rod 30' is located at the end of the holder rod 28' away from the walking beam 26, to take up the movement of the counterweight 29 as the same approaches the spring end of the holder rod 28'. The shaft 31 65 pivoted in frame 27 which carries the walking beam or crank 26 has affixed to itself an arm 32 which in turn is connected with a rod 33 passing slidably through a guide 34. The rod 33 bears two spaced guide plates 70 35 and 36, the one, 35 being a connecting guide plate, the other 36 being a braking guide plate, at and near respectively the end of said rod 33 opposite to the end where said rod 33 meets the arm 32. The guide plates 75 35 and 36 partake of the to and fro movements of the rod 33 by the action of the arm 32 and walking beam 26 and serve to actuate the contact lever 37 upon the pivot 38 and shift the contact brush 39 carried thereby 80 and thus make and break the connection between contact arm 40 and contact brush 39. These three parts 39, 40 and 41 form 85 part of the means whereby the electric current proceeds to the solenoid 17 when the contact brush 39 is closed. Contact brush 39 is continuously in contact relation with contact arm 41 which latter is connected to the source of energy by wire 42. Contact arm 40 connects with wire 43, which is the 90 conductor of electrical energy to the coil of wire 20 of solenoid 17. Wire 44 is the conductor for electric current moving away from solenoid 17. The space between the exterior surface of plunger 13 and the interior surface of bobbin 19 of solenoid 17 95 is indicated by 45. When the arm 32 is in a position nearer to main base 10, the contact lever 37 is actuated to swing on pivot 38, thereby moving the contact brush 39 100 out of contact with the contact arm 40 and thereby breaking the electric circuit and de- 105 110

energizing the solenoid 17; as a result of this action, the plunger 13 is released in the solenoid 17 so that said plunger may be moved out of the solenoid by the counter-weight 29 or other equivalent mechanism acting upon the walking beam 26. With the rod 33 moving away from main base 10, the contact lever 37 is actuated to come back so that contact brush 39 again engages the contact arm 40 and closes the electric circuit so that the electric current proceeds into the solenoid 17 along the wire 43; by this electrical energization of the solenoid 17 the plunger 13 is caused to be again drawn into said solenoid 17. The plunger 13 may be connected to various forms of mechanism to accomplish divers objects.

In the electromagnet which I employ, the plunger 13 is perforated with apertures as shown at 14, thus giving external and internal surface area and thereby affording better conditions for electric action. This plunger is hollow and bears against the guide rod 21 only at each end of the plunger 13 thereby reducing friction to a minimum with respect to the guide rod 21. This plunger does not come into actual contact with the surrounding bobbin 19 of the solenoid, so that friction between the surface of the plunger 13 and the bobbin of the solenoid 17 is also eliminated; in addition, by the omission of this friction which would occur were the plunger to touch the bobbin 19 of the solenoid, the electric and magnetic forces are free to exert their influence without the interference that would otherwise be produced between the said plunger and solenoid. Fur-

ther, the surrounding air existing in the space between the plunger and the solenoid and in the apertures in the plunger itself aids in keeping the plunger and solenoid free in considerable measure from a heated condition, which latter condition works to the disadvantage of electromagnets that are now in use. By means of my improvement in electromagnets, I provide for the operation of same with very much less heating effect, and with relatively increased wattage.

I claim:

An electrical power appliance comprising a solenoid, a base member on which the solenoid is supported, said base member having holes in its side walls, upstanding side rods disposed at diametrically opposite points on the solenoid and projecting upwardly therefrom, a cross bar connecting said side rods, a guide rod extending axially through the solenoid and connected at its upper end with the cross bar at an intermediate point in the latter and at the lower end secured to the base, and a hollow plunger in surrounding relation to and having slide bearings mounted upon the guide rod, the plunger being reduced in diameter below the bore of the solenoid to provide a minute clearance space between it and the solenoid and having series of air passages in surrounding relation to the slide bearings and lateral openings effecting communication interiorly between it and the clearance space.

In testimony whereof I have hereunto set my hand.

ROBERT A. BLAKE.
